US00D985537S

(12) **United States Design Patent** (10) **Patent No.:** **US D985,537 S**
Li (45) **Date of Patent:** **** May 9, 2023**

(54) **REMOTE CONTROLLER**

(71) Applicant: **SHANTOU FENGMA TOY INDUSTRY CO., LTD.**, Shantou (CN)

(72) Inventor: **Haibo Li**, Shantou (CN)

(73) Assignee: **SHANTOU FENGMA TOY INDUSTRY CO., LTD.**, Shantou (CN)

(**) Term: **15 Years**

(21) Appl. No.: **29/774,113**

(22) Filed: **Mar. 15, 2021**

(51) LOC (14) Cl. **14-03**

(52) U.S. Cl.

USPC **D14/218**

CLAIM

The ornamental design for a remote controller, as shown and described.

DESCRIPTION

FIG. 1 is a perspective view of a remote controller showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the remote controller that form no part of the claimed design.

1 Claim, 8 Drawing Sheets
